OIL BURNER ASSEMBLIES

Eugene A. Roeske, St. Louis, Mo., assignor to Emerson Electric Co., St. Louis, Mo., a corporation of Missouri
Filed Mar. 29, 1965, Ser. No. 443,441
2 Claims. (Cl. 103—6)

This invention relates to oil burners of the type in which a combustible mixture of air and oil is introduced into a furnace. It relates particularly to that part of an oil burner assembly which supplies the air and oil to the system immediately before the oil and air are introduced into the furnace.

In oil burners commonly used commercially, it is customary to provide a centrally located blower, with a blower housing, outside and at one side of which is an electric motor and outside and at the other side of which is an oil pump. A blower wheel inside the housing, is mounted on the motor shaft, which extends through the housing. The motor is either fully enclosed, or is provided with a fire pan extending beneath it. The motor shaft is coupled by means of a long coupling to the shaft of the oil pump.

This arrangement requires a considerable space, and the use of at least four bearings in the usual arrangement. One of the objects of this invention is to provide an oil burner assembly which is more compact than assemblies known heretofore, and at the same time is more efficient.

Another object is to provide an oil burner assembly in which the heat generated within the electric motor is utilized to improve the efficiency of the oil burner and at least some of its components.

Other objects will become apparent to those skilled in the art in the light of the following description and accompanying drawing.

In accordance with this invention, generally stated, an oil burner assembly is provided, which includes an electric motor having a wound stator and a motor housing in heat transfer relation with the wound stator. An oil chamber is defined within the housing in heat transfer relation therewith, and fuel oil to be supplied immediately to the furnace is passed through the oil chamber to pick up the heat from the wound stator prior to the oil's being introduced to the furnace. This arrangement not only permits the oil to be preheated, but it improves the efficiency of the atomization and combustion of the oil, and it also has the effect of dissipating the heat from the motor, so that a smaller motor can be used than could otherwise be used for the purpose.

The wound stator is mounted within the blower housing itself, and a blower wheel, connected to be driven by the motor shaft, is provided with blades which encompass the wound stator, within a passage defined between the stator and the blower housing. The blower housing is continuous along the under side of the motor, so as to form a fire pan for those embodiments of the assembly in which open motors are used. The blower housing is open at one end to admit air, and is provided with a discharge opening so located that the air drawn through the inlet openings by the blower, passes in heat transfer relation to the wound stator as it moves through the passage between the stator and the blower housing, so as to be preheated before it reaches the furnace, and to dissipate heat from the wound stator.

The motor housing includes an end shield which carries a bearing in which a rotor shaft (the motor shaft) is journaled. In one embodiment shown and described, the end shield is provided with an elongated passage which serves as the oil chamber. In another embodiment, the end shield serves as one closure member of a totally enclosing motor housing, the interior of which serves as the oil chamber so that fuel oil introduced to the oil cham-

2

ber is in direct contact with the windings of the wound stator.

In the preferred embodiment, the means for introducing to the furnace the oil component of the flammable mixture includes a gear pump of the internally toothed type, having a suction and a discharge side. The suction side of the pump is connected to communicate with the oil chamber. In such a pump, an internally toothed gear is journaled within a pump housing, which, in the preferred embodiment, is an integral part of the end shield. In this embodiment, the pump is closed by a pump housing cover, which also contains a valving device and fittings for connections to a fuel oil conduit to a nozzle in the furnace and to a source of fuel oil. A manifold with suction and discharge manifold parts may be provided in the cover or in the end shield, or both depending upon the embodiment.

While the gear pump type of burner assembly is preferred, for reasons of simplicity, efficiency, and compactness, many of the features of this invention are applicable to other types of oil introducing devices, such as educators e.g. so-called low pressure systems.

In the drawing:

FIGURE 1 is a sectional view of one embodiment of oil burner assembly constructed in accordance with this invention;

FIGURE 2 is a sectional view taken along the line 2—2 of FIG. 1;

FIGURE 3 is a sectional view taken along the line 3—3 of FIG. 1; and

FIGURE 4 is a sectional view showing still another embodiment of oil burner assembly of this invention.

Referring now to the drawing, and particularly to FIGS. 1, 2 and 3 for one illustrative embodiment of oil burner assembly of this invention, reference numeral 1 indicates an oil burner equipped with an assembly of this invention. The oil burner 1 includes a furnace plate 2, a transformer 3 which forms part of the conventional ignition system, an air duct 4, an oil discharge conduit 5, which terminates in a spray nozzle, not here shown, and an assembly 10.

The furnace plate 2, transformer 3, air duct 4 and oil discharge tube 5 are all standard commercial components, and, as such, form no part of this invention.

The assembly 10 includes a motor 20, a blower assembly 60, a pump 80, and a valve assembly 90.

The motor 20, in this embodiment, includes a heavy end shield 21, an end bell 22, a wound stator 23, a rotor 24 and a rotor shaft 25. The end shield 21 and end bell 22 together form a motor housing 30. The rotor shaft 25 is journaled, at one side of the rotor 24, in a bearing 26 in a hub section 27 of the end shield 21, and on the other side of the rotor, in a bearing 28 in a boss 29 on the end bell 22. The end bell 22 is deep, and is provided with an inner shoulder 31 against which a laminated core 35 of the stator 23 rests to locate the stator with respect to the motor housing 30. The end bell 22 has an exterior rabbet at its open end, which mates with a flange on the end shield 21, and forms, with the aid of an O-ring 33, an oil tight oil chamber 37. Windings 36, extending within slots in the core 35 and having end turns projecting at each end from the core 35, are exposed within the oil chamber 37. Pins 38, on either side of the core 35, serve to hold back the end turns of the windings 36, so that they will not interfere with end rings 39 of the rotor 24. The end ring 39 adjacent the hub 27, in the embodiment shown, has formed in its blade 40, which help circulate the oil in the oil chamber 37.

A passage 42 in the boss 29 of the end bell 22 leads between the bearing 28 and a gland 43, to permit oil to lubricate the outer end of the bearing 28. An oil supply passage 41 in the hub 27 of the end shield 21 communi-

cates at one end with the oil compartment 37, and at its other end with a suction manifold port 45. A passage 46 in the end shield 21 communicates at one end with the oil chamber 37 and at its other end with an enlarged tapped socket 47, into which a fitting of an oil supply conduit, not here shown, is connected. The oil supply conduit is in turn connected to a source of oil, such as the usual domestic oil burner tank, also not here shown.

The end shield 21 also has a mounting flange 48 around its outer periphery.

A screen 49 is positioned within the compass of the end bell 22, with one, inner margin of the screen bearing against the boss 29, and an outer margin bearing against a radial surface of the stator core 35. A passage 51, extends through the stator core 35, communicating at one end with the oil passage 46, and its other, with a part of the oil chamber 37 between the end bell 22 and the screen 49.

The motor 20 is mounted on and largely within a blower housing 61. The blower housing 61 includes side walls 62 and 63, and a scroll-defining web 64. The web 64 is imperforate, and forms an enclosure constituting a fire pan around the lower part of the motor 20. The wall 63 has a motor-receiving opening, within which end shield 21 is seated with the flange 48 in engagement with the opening-defining margin of the wall 63, as shown in FIGURE 1. The motor is held in position by any suitable means not here shown, which may take the form of bolts and spring-nuts such as is illustrated in connection with the embodiment shown in FIGURE 4. The wall 62 is provided with a multiplicity of radially extending wedge shaped openings 64' and a damper plate 65, mounted on the wall 61 by means of a bolt 66, is provided with similar holes 67, which, upon selective rotation of the plate 65, are either aligned with the openings 64' to provide unhindered ingress of air, or offset with respect to the openings 64' so as to throttle the ingress of air. The upper part of the housing 61 communicates with the air duct 4.

Within the housing 61 a blower wheel 70 is mounted, by means of a hub 71, on one end of the rotor shaft 25. The blower wheel includes a spider 72, welded to the hub 71 at one end and integral at its other end with a rim 73, blades 75, integral at one end with the rim 73 and at the other end with an outer rim 76. As is readily apparent from FIGURE 1, the blades 75 embrace the motor housing 30, and revolve within a passage 78 defined between the motor housing 30 and the web 64 of the blower housing 61.

The pump 80 includes the manifold port 45 formed in the end shield hub 27, a discharge balancing manifold 81, also formed in the hub 27, an externally toothed gear 82, keyed to one end of the shaft 25, an internally toothed gear 83, and a pump housing 84, integral with the hub 27, in which the internally toothed gear 83 is journaled for rotation. An O-ring 85, seated in an annular groove 86 in a flat 87 on the face of the end shield 21, serves to seal the pump, when a flat face of a cover plate 92 made integral with a casing 95, of the valve assembly 90, is fastened to the end shield 21 by means of studs 96. The cover plate 91 has in its two manifold ports, a suction balancing manifold port 93 and a discharge manifold port 94. The suction balancing manifold port 93 communicates with the suction side of the pump 80 at one end, and at its other end with a valve bore 97 on one side of valve piston 98 slideably mounted in the bore 97. The discharge manifold port 94 communicates at one end with the discharge side of the pump 80, and at its other end, with the valve bore 97 on the other side, axially, of the valve piston 98. The valve piston 98 has, on the discharge side, a valve stem 99 with a conical head 100, which seats against a valve seat 101 in a fitting 102, threadedly mounted in the valve casing 95. The fitting 102 has an axially directed passage 103, communicating at one end with a passage in the valve seat 101, and at its other, with the oil discharge conduit 5. On the suction side of the

valve piston 98, the piston is provided with a spring boss 105, which positions a helical spring 106. The helical spring 106 bears at one end on the under side of the valve piston 98, and, at its other end, on a stop washer 107. Stop washer 107 bears against an end of an adjusting screw 108, which is threaded into the lower end of the casing 95 in axial alignment with the bore 97. The adjusting screw 108 is held in position by nuts 109.

On the discharge side of valve piston 98, a gauge fitting socket 112 is provided. The socket 112 is normally plugged, although a pressure gauge can be mounted permanently to indicate the pressure of oil being discharged from the pump 80 as the oil passes through the bore 97 on the pressure side of the valve piston 98.

The valve assembly is provided with bypass passages so that when the pressure from the pump exceeds a predetermined limit by the setting of spring 106, the fuel oil is bypassed, either back to the oil supply conduit or tank, or to the suction side of the pump, so as to prevent injury to the system. This, however, is standard in hydraulic systems, and is not here illustrated.

In the operation of the assembly illustrated in this embodiment, assuming that the openings 64' and 67 have been adjusted so as to admit the desired amount of air, that the socket 112 is closed either by a plug or gauge, that the adjusting screw 108 has been adjusted to provide the amount of compression of the helical spring 106 required to give the desired flow of oil, and that, by virtue of the elevation of the oil supply tank, the motor housing, i.e. the oil chamber 37, is filled with fuel oil. When the motor is energized from a source of alternating current, not here shown, the stator windings immediately begin to heat, even as the motor is starting. The rotor 24 begins to rotate, turning the externally toothed gear 82 and the internally toothed gear 83, to begin pumping fuel oil from the oil chamber 37, in through the passage 41 and suction manifold port 45 and out through the discharge manifold port 94. As this oil is displaced, fresh oil, from the source, comes through the passage 51 in the stator core 35, which is heated by the coils 36, through the screen 49, between the rotor and stator and through a passage 53 in the rotor, to the passage 41. It can be seen that the oil is in intimate contact with the windings 36 themselves, and the rotation of the rotor 24 insures a vigorous circulation of the fuel oil within the oil chamber 37.

The rotation of the rotor 24 also causes rotation of the blower wheel 70, whereby the blades 75 are driven around the motor casing 30. The motor casing 30 is in direct heat transfer relation with the stator core 35, and in heat transfer relation by radiation, convection and conduction through the fuel oil with the windings 36. The casing 30, accordingly, heats sensibly, and, in turn, heats the air which is drawn through the openings 64' into the fan wheel 70, over the casing, and out through the blades 75 to the duct 4, hence into the furnace. The heating of the fuel oil by the stator windings before the oil is delivered to the furnace, and the heating of the air, not only improve the efficiency of the atomizing and efficiency of the burning of the fuel oil, but also serve to cool the motor 20. It is also to be noted that in the construction of this embodiment of oil burner assembly, only two bearings are required, no couplings between shafts, and only half or less of the space occupied by the conventional oil burner assembly.

Referring now to FIG. 4 for another embodiment of oil burner assembly of this invention reference numeral 110 indicates the assembly part of an oil burner. The assembly 110 is incorporated into an oil burner of the same type as that shown in FIG. 1. The assembly 110 includes a motor 120, a blower 160, a pump 180 and a valve assembly 190.

The motor 120, in this embodiment, includes an outer end shield 121, an inner end shield 122, a stator housing 133, a wound stator 123, a rotor 124, and a rotor shaft 125. The outer and inner end shields are rabbeted to

receive the stator housing 133, and held together by through-bolts 134, in this respect being conventional. The inner end shield 122 carries a conventional bearing assembly 126, which includes felt oil rings 128. A lubricating oil passage 129 extends radially through the inner end shield 122, and communicates with the bearing assembly 126, so that the bearing assembly can be oiled.

The rotor shaft 125 is journaled at one end in a sleeve bearing in the bearing assembly 126, and projects through and beyond the inner end shield 122, to carry a blower assembly 170 which is identical in every respect with the blower assembly 70 of the embodiment shown in FIG. 1.

The motor 120 is mounted on and in part within the blower housing by means of bolts 135 extending through holes in the end shield 121 and corresponding holes in the blower housing, and spring nuts 136.

The outer end shield 121 has a heavy hub section 127. The hub 127 carries a bearing 130, in which the other end of the rotor shaft 125 is journaled and through and beyond which it extends. A gland drain passage 137 extends through the hub 127 from a sealing gland 138 to the suction side of the pump 180. The hub 127 is provided with a relatively large annular channel 131, concentric with the bearing 130 and spaced radially outwardly from and extending around a pump housing 184, integral with the hub 127. An accordian-folded screen 139 is seated in the channel 131. Radially outboard of the channel 131 is an annular groove 132, in which an O-ring is seated. The groove 132, channel 131, and pump housing 184 all open through a flat face 144 of the hub 127, and are all closed by a complementary face 191 of a housing 192 which is part of the valve assembly 190. The housing 192 is bolted to the face of the hub 127 of the outer end shield 121 by means of studs, not here shown, but which may be similar to the studs 96 of the embodiment shown in FIGS. 1 and 2.

The pump 180 of this embodiment is substantially identical with the pump 80 of the embodiment shown in FIGS. 1-3. It includes a suction manifold port 145 formed in the end shield hub 127, a distance balancing manifold 181, also formed in the hub 27, an auxiliary suction manifold port 193 in the valve housing 192, and a discharge manifold port 194, also in the valve housing 192. An externally toothed gear is keyed to the end of the shaft 125, within the housing 184, and an internally toothed gear is journaled in the housing 184, exactly as the gears 82 and 83 shown in FIGS. 1 and 2.

A fuel oil suction passage 141 communicates at one end with the suction manifold port 145, and at its other, with the channel 131, which, closed by the cover of valve housing 192, constitutes an oil chamber for the reception of fuel oil. An internally threaded fitting socket 147 is provided in the valve housing 192, which socket communicates, through a passage 146, with the chamber 131. As in the other embodiment, the socket 147 receives an externally threaded fitting on a fuel oil supply conduit communicating with a source of fuel oil, not here shown.

While there are some slight differences in configuration of the parts, notably the valve seat and the valve head, the construction and arrangement of the valving parts of the valve assembly 190 are essentially the same as those of the embodiment shown in FIG. 1.

It can be seen that in the embodiment shown in FIG. 4, the hub 127 is in heat transfer relation to the windings 65 of the stator 123, and the fuel oil, instead of circulating within the motor housing, circulates, through the screen within the chamber 131, where it picks up heat from the windings.

The operation of the oil burner assembly shown in FIG. 4 is substantially the same as that of the embodiment shown in FIGS. 1-3. If the amount of heat ab-

sorbed by the fuel oil in the chamber 131 is somewhat less than the amount absorbed by the fuel oil within the chamber defined by the motor housing itself in the first embodiment, the air, in the second embodiment, will be heated the more, and the greater temperature gradient between the initial temperature of the air and the temperature of the motor will promote greater heat transfer, hence greater cooling of the motor by the air and greater heating of the air by the motor than is accomplished by the embodiment shown in FIG. 1.

Numerous variations in the construction of the oil burner assembly of this invention, within the scope of the appended claims, will occur to those skilled in the art in the light of the foregoing disclosure. Merely by way of example, various other types of blower construction, pump construction and valve construction can be used; the burner itself can be of the low pressure, education type, in which a pump of the gear type plays a lesser and perhaps nonexistent role, but in which, nevertheless, the fuel oil can be drawn through a fuel oil chamber in heat-transfer relation to the windings of the motor; or a single bearing motor might be utilized. These are, as has been indicated, merely illustrative of variations which will occur spontaneously to those skilled in the art in the light of the foregoing disclosure.

Having thus described the invention, what is claimed and desired to be secured by Letters Patent is:

1. An oil burner assembly comprising an electric motor having a wound stator, a rotor including a rotor shaft, a motor housing including an end shield in heat transfer relation to the wound stator, a pump having an impeller, a pump housing, and suction and discharge manifold ports in said housing, a major portion of said pump housing being integral with said end shield, said impeller being connected to be driven by said rotor shaft, said motor housing having an oil chamber within it, in heat transfer relation to said wound stator, whereby fuel oil in said chamber is heated by said wound stator when the motor is in operation, said chamber communicating with one of said manifold ports, a blower housing encompassing the said motor and spaced radially from said wound stator to define therewith a passage, and a blower wheel mounted to embrace said wound stator, connected to be driven by said rotor shaft, and arranged to blow air through said passage.

2. An oil burner assembly comprising an electric motor having a wound stator, a rotor including a rotor shaft, a motor housing in heat transfer relation with the said wound stator, an oil pump having a pumping part connected to said rotor shaft and suction and discharge manifold ports, an oil chamber defined within said housing in heat transfer relation therewith, whereby fuel oil in said chamber is heated by said wound stator when the motor is in operation, said chamber communicating with one of said manifold ports, a blower housing encompassing the said motor and spaced radially from said wound stator to define therewith a passage, and a blower wheel mounted to embrace said wound stator, connected to be driven by said rotor shaft, and arranged to blow air through said passage.
